UNITED STATES PATENT OFFICE

113,664

DESIGN FOR A CASING FOR A PUMP UNIT

Park Fuller, Berkeley, Calif., assignor to Micro-Westco, Inc., Bettendorf, Iowa, a corporation of Delaware

Application June 29, 1938, Serial No. 78,148

Term of patent 14 years

To all whom it may concern:

Be it known that I, Park Fuller, a citizen of the United States, residing at Berkeley, in the county of Alameda and State of California, have invented a new, original, and ornamental Design for a Casing for a Pump Unit, of which the following is a specification, reference being had to the accompanying drawing, forming a part thereof.

In the drawing:

The figure is a perspective view of a casing for a pump unit showing my new design, and the other side of the casing is substantially like the side shown in the figure.

I claim:

The ornamental design for a casing for a pump unit, substantially as shown and described.

PARK FULLER.
